UNITED STATES PATENT OFFICE

172,121

HELICOPTER PROPELLER WITH JET ENGINES

Stefan Apostolescu, New York, N. Y.

Application May 20, 1953, Serial No. 25,114

Term of patent 14 years

(Cl. D71—1)

To all whom it may concern:

Be it known that I, Stefan Apostolescu, residing at New York city, county of New York, and State of New York, have invented a new, original, and ornamental Design for a Helicopter Propeller with Jet Engines, of which the following is a specification, reference being had to the accompanying drawing, forming part thereof.

Fig. 1 is a top plan view of a helicopter propeller with jet engines showing my new design.

Fig. 2 is a side view thereof.

Fig. 3 is a bottom plan view thereof.

Fig. 4 is a rear end view thereof.

Fig. 5 is a front end view thereof.

Fig. 6 is a sectional view taken on the plane of the line 6—6 of Fig. 2.

I claim:

The ornamental design for a helicopter propeller with jet engines, as shown.
